UNITED STATES PATENT OFFICE.

WILLIAM A. FROECKMAN, OF ST. LOUIS, MISSOURI, ASSIGNOR OF ONE-HALF TO
PETER P. FINNEGAN, OF ST. LOUIS, MISSOURI.

COMBINED TELEGRAPH, SIGNAL, AND TELEPHONE SYSTEM.

1,004,767.

Specification of Letters Patent.

Patented Oct. 3, 1911.

Application filed May 5, 1910. Serial No. 559,562.

To all whom it may concern:

Be it known that I, WILLIAM A. FROECKMAN, a citizen of the United States, residing at St. Louis, Missouri, have invented a certain new and useful Improvement in Combined Telegraph, Signal, and Telephone Systems, of which the following is a full, clear, and exact description, such as will enable others skilled in the art to which it app pertains to make and use the same.

This invention relates to combined telegraph, signal and telephone systems such as are used by city fire departments for establishing communication between the central office or headquarters of the department and the various engine-houses or sub-stations at which the fire engine companies are stationed. The system that is generally used in most city fire departments for establishing communication between the central office and the engine-houses comprises a plurality of telephone circuits, telegraph circuits, commonly termed "joker circuits," and bell circuits or "sub-joker circuits," the engine-houses or sub-stations in a certain district being connected to one of each of said different circuits. The telephone circuits are of course used for carrying on conversations between the head-quarters and the engine-houses, and the telegraph circuits and the bell circuits are used for sending out alarms from the central office, each engine-house being equipped with a telephone, a telegraph instrument, and a bell or other suitable signal, which telegraph instrument and bell are connected in series with the telegraph circuit and the bell circuit, respectively, of the district in which the engine-house is located. In view of the fact that the engine-houses are connected in series with the central office or exchange, it is often difficult to locate a break in the system, and during the time a circuit is open all of the instruments on that particular circuit are out of service.

One object of my invention is to provide a combined telegraph, signal and telephone system which is so designed that a break in any circuit of the system can be located quickly.

Another object is to provide a system of the character described which is so designed that a break in one of the circuits thereof

has no effect on the instruments which are connected to said circuit between the central exchange and the point where the break occurs.

Another object is to provide a system of the character described which comprises automatic means for notifying all of the sub-stations beyond a break in the telegraph circuit that their telegraph instruments are out of service. And still another object is to provide a system of the character described that comprises a sufficient number of metallic conductors between the central station and the sub-stations to enable temporary communication to be established between the central office and sub-stations under practically all conditions by cross-connecting an instrument at the sub-station that is on a dead line with a live line through which current is passing.

Other objects and desirable features of my invention will be hereinafter pointed out.

The figure of the drawing is a diagrammatic view of a system constructed in accordance with my invention.

Referring to said drawing, the reference character A designates the central office or headquarters of a city fire alarm department, and B and C designate two of the engine-houses or sub-stations of the department which receive instructions from the central office or exchange. Each of the engine-houses is provided with a telegraph instrument 1 which may either be a recording instrument, as herein shown, or merely a sounder, a bell or audible signal 2, a grounded striking key 3, and a telephone 4, all of said instruments being of any preferred type or design. The central office A is provided with a telephone switch-board 5, a key 6 for operating the telegraph instruments 1 and the bells 2 in the various engine-houses, and also a grounded signal 7 which is adapted to be operated by the striking keys 3 at the various engine-houses of the department.

Instead of connecting the telegraph instruments and signals at the engine-house in series with the central exchange A, as has heretofore been the general practice, I connect said devices in multiple with metallic conductors that lead from the central exchange.

break is between houses B and C for any 5 break beyond B has no effect on the instruments at said house. It is very seldom that both sides of a line will be broken at the same time but in case this unusual condition exists the telegraph instrument can be cross-connected or tapped onto either side of the bell circuit 9 or the telephone circuit 10 in any suitable manner, as, for example, by 10 means of the plug cords 30 and 31 at the sub-stations and central exchange which operate with the plug sockets 8^a, 9^a and 10^a that are arranged in the telegraph circuit, the bell circuit and the telephone circuit, respectively.

While the bell circuit is primarily used for operating the signals 2 at the engine-houses and also for forming one side of the connecting circuit between the striking keys 20 3 and the signal 7, this bell circuit can also be used for telephoning in case a break occurs in the telephone circuit 10 by plugging into the bell circuit and actuating the magneto-generator 23 which sends out a pulsating current over the bell circuit 9 and through the condenser 24 to the magneto-bell 25 which is grounded, it being, of course, understood that each engine-house is equipped with a magneto-bell and condenser 25 and suitable telephone jacks for establishing cross-connections between the various circuits.

As previously stated, one of the principal 35 advantages of a system of the character which I have described is that it is a very simple matter to locate a break in any of the circuits owing to the fact that the multiple connection between the circuits and instruments causes all of the instruments beyond the break to become inoperative and prevents the break from affecting the instruments arranged on the other side of same, namely, the instruments located between the break and the source of electrical supply. 40 The fact that only the instruments that are located beyond the break are rendered inoperative is also a very desirable feature, and still another exceedingly desirable feature of my improved system is that there are 45 a sufficient number of metallic conductors between the central exchange and the various sub-stations to enable a metallic connection to be established between said sub-stations and central stations under practically 50 all conditions. The means for automatically notifying the sub-stations whenever a break occurs in the telegraph circuit is a desirable feature but it is not absolutely essential to the successful operation of my system. It is 55 immaterial what particular kind or type of instruments or apparatus the sub-stations and central exchange are provided with for my invention, broadly stated, consists in a 60 combined telegraph, signal and telephone system comprising sub-stations equipped

with telegraph instruments, signals and telephones that are connected in multiple with the circuits which energize them.

While I have herein stated that batteries are used for energizing the various circuits, 70 it will, of course, be obvious that generators or any suitable means for producing electrical currents could be substituted for the batteries.

Having thus described my invention, what 75 I claim as new and desire to secure by Letters Patent is:

1. A fire alarm system, comprising a telegraph circuit, a signal circuit and a telephone circuit, corresponding instruments at 80 the sub-stations or engine-houses connected in multiple with their respective circuits, and means at the engine-houses for establishing cross connections between said circuits so as to utilize one side of a circuit to form a return around a break in a different circuit. 85

2. A fire alarm system, comprising separate and distinct metallic circuits for telegraphing, telephoning and signaling, appropriate instruments at the engine-houses 90 or sub-stations of the system which are connected in multiple with their respective circuits, a common battery at the central exchange for energizing the telegraph circuit and the signaling circuit, and means for 95 utilizing one side of either of said circuits to form a return around a break in a different circuit.

3. In a fire alarm system, a metallic circuit which leads from a central exchange to 100 sub-stations or engine-houses, telegraph instruments at the sub-stations connected in multiple with said circuit, signal circuits at said sub-stations provided with signals, relays arranged in said metallic circuit for 105 controlling said signal circuits, and means under control of the operator at the central exchange for sending out current of a certain voltage to operate said signals without operating said telegraph instruments and 110 also a current of a different voltage to operate said telegraph instruments.

4. In a system of the character described, a telegraph circuit leading from a central exchange to a sub-station, a telegraph instrument, and a signal at said sub-station connected in multiple with said circuit, and means under control of the operator at the central exchange for sending out current of a certain voltage to operate said signal without operating said instrument and also a current of a different voltage to operate said instrument. 115

5. A fire alarm system comprising a central exchange, a plurality of sub-stations or 120 engine-houses, said central exchange and sub-stations or engine-houses being each provided with a telegraph instrument, a signaling instrument and a telephone instrument, a plurality of separate and distinct metallic 125

electrical circuits connecting the central exchange instruments with the sub-station instruments by multiple connection, and means for utilizing any one of said circuits for operating any one of said instruments.

6. A system of the character described, comprising a telegraph circuit and a bell circuit leading from a central exchange to sub-stations, telegraph instruments and bells at 10 said sub-stations connected in multiple with said telegraph circuit and bell circuit, respectively, a common source of electrical energy at the central exchange for supplying current to said circuits, signals at the

central exchange and sub-stations which are 15 adapted to be operated by said circuits, an independent means for energizing said telegraph circuit, an independent means for energizing said bell circuit, and means for utilizing either of said circuits for operating 20 any of said instruments.

In testimony whereof I hereunto affix my signature in the presence of two witnesses, this second day of May 1910.

WILLIAM A. FROECKMAN.
